ATTORNEY

UNITED STATES PATENT OFFICE.

JOHN BUSHKOVSKI, OF COLUMBUS, NEW MEXICO.

DESIGN FOR A PLACARD.

50,647.

Specification for Design. Patented Apr. 24, 1917.

Application filed January 12, 1917. Serial No. 142,116. Term of patent 14 years.

To all whom it may concern:

Be it known that I, JOHN BUSHKOVSKI, a citizen of the United States, residing at Columbus, in the county of Luna and State of New Mexico, have invented a new, original, and ornamental Design for Placards, of which the following is a specification, reference being had to the accompanying drawing, forming a part thereof.

The figure is a plan view of a placard, showing my new design.

I claim:

The ornamental design for a placard, as shown.

JOHN BUSHKOVSKI.

Witnesses:

T. F. TAYLOR,
C. O. BAGBY.
